(Cl. D61—1)

Fig. 1

Fig. 2

Fig. 3

Figure 1 is a perspective view of a photographic copying attachment for a camera or similar article showing my new design;

Figure 2 is a side elevational view, the opposite side being similar; and

Figure 3 is a rear elevational view thereof.

The broken line showing of a representative camera is for illustrative purposes only.

The dominant features of my design are shown in solid lines in the drawing.

I claim:

The ornamental design of a photographic copying at-

achment for a camera or similar article, substantially as shown and described.
